PING LEE, OF WINDSOR, ONTARIO, CANADA

DETACHABLE RUBBER HEEL

Application filed March 29, 1929, Serial No. 351,069. Renewed March 30, 1931.

My invention relates to improvements in detachable rubber heels and the object of the invention is to devise simple means whereby a rubber heel may be quickly attached or detached from the heel of the shoe and the contacting faces of which will cling closely together, and it consists essentially of the arrangement and construction of parts as hereinafter more particularly explained.

Fig. 1 is a perspective view of a fragmentary portion of a boot or shoe showing the heel and my rubber heel attached thereto.

Fig. 2 is a perspective view of the boot or shoe heel and rubber heel separated.

Fig. 3 is a sectional view through the shoe heel and rubber heel showing the detachable connection therebetween.

In the drawings like characters of reference indicate corresponding parts in each figure.

1 indicates a portion of a boot or shoe provided with the usual heel 2. 3 is an open plate which fits against the face of the heel, having its outer edge slightly spaced from the outer edge of the heel.

4 are dome fastener members, preferably formed integral with the plate 3 and provided with central orifices 4^x through which securing nails 5 extend into the heel 2 of the boot or shoe. 6 is a rubber heel which is provided with a recess 7, conforming to the shape of the plate 3, and in which is inserted an opposing plate 8 carrying the opposing members 9 of the dome fastener members 4.

The members 9 are embedded in the rubber of the heel 6 and the depth of the recess 7 in which the plate 8 is inserted is slightly greater than the combined thickness of the plates 8 and 3.

It will thus be seen that when the rubber heel 6 is applied to the shoe heel 2, and the dome fastener members 4 and 9 pressed together to engage in the usual manner common to all dome fastener members that the rubber of the heel particularly adjacent the outer edge of the recess 7 will be compressed, thereby insuring of a close fit be-

tween the face of the rubber heel and the face of the shoe heel, so that there will be no danger of moisture or any foreign matter entering between the rubber heel and the shoe heel which would have a tendency to gradually loosen the rubber heel, a detrimental effect which is common to all rubber heels as heretofore made.

It may be further pointed out that by the detachable construction set forth above, when the heels become worn on one side they may be readily detached and interchanged so that the worn portion which is generally on the outer side of the heel, when the heel is placed on the heel of the other boot will be on the inside so that the unworn portion of the heel would then receive the wear, and thus even up the heel, and when such part has become worn it may be again interchanged, this operation being repeatedly done so as to materially increase the life of the heel. It will also be seen that the interchanging operation may be performed almost instantaneously, so that there will be not loss of time.

What I claim as my invention is:

The combination with a shoe heel of a plate provided with dome fastener members secured to the face of the heel, a rubber heel provided with a recess conforming to the shape of the aforesaid plate, an opposing plate fitting within the base of the recess and provided with dome fastener receiving members, such recess being of a depth greater than the combined thickness of the opposing plates so that when the dome fastener members are engaged the edge portion of the rubber heel face is held compressed against the face of the shoe heel.

PING LEE.
